UNITED STATES PATENT OFFICE.

GEORGE W. OSBORN, OF GRANITE CITY, ILLINOIS, ASSIGNOR, BY DIRECT AND MESNE ASSIGNMENTS, OF ONE-FOURTH TO WILLIAM C. URBAN, OF GRANITE CITY, ILLINOIS, AND ONE-HALF TO HOYT METAL COMPANY, OF ST. LOUIS, MISSOURI, A CORPORATION OF MISSOURI.

EXPANDING MANDREL.

1,293,525.

Specification of Letters Patent.

Patented Feb. 4, 1919.

Application filed July 16, 1917. Serial No. 180,762.

To all whom it may concern:

Be it known that I, GEORGE W. OSBORN, a citizen of the United States of America, a resident of Granite City, in the county of Madison, State of Illinois, have invented certain new and useful Improvements in Expanding Mandrels, of which the following is a full, clear, and exact description, reference being had to the accompanying drawings, forming a part of this specification.

My invention relates to improvements in expanding mandrels adapted for use in securing work to lathes and the like. The main object of the invention is to produce a simple device of this kind adapted to be expanded and contracted very easily, and very quickly, so that the work can be quickly applied to and removed from the machine. The new device includes operating means whereby the mandrel is expanded and contracted, and the parts are preferably so constructed that these operations can be performed very rapidly without stopping the machine.

Figure I is a plan view of an expanding mandrel constructed in accordance with my invention, also showing the means for rotating the mandrel and the means for expanding and contracting the same.

Fig. II is a side elevation of the parts shown in Fig. I.

Fig. III is a side elevation, partly in section.

Fig. IV is an enlarged transverse section of the mandrel.

Fig. V is a longitudinal section illustrating a modification.

Fig. VI is an end view of the mandrel shown in Fig. V.

A designates a frame provided with bearings 1 for a rotatable hollow shaft 2. Power may be transmitted to the hollow shaft 2 through the medium of a cone pulley 3 or gear wheels 4 and 5, all of which are mounted on said shaft.

The expanding mandrel preferably comprises a rigid, or non-yielding, work-receiving sleeve B having a tapered portion 6 which frictionally engages a correspondingly tapered face at one end of the hollow shaft 2. The non-yielding sleeve B is provided with longitudinal slots for the reception of elongated gripping blocks 7, the lat-

ter being arranged radially to the axis of said sleeve, and they may be moved toward and away from said axis. When the device is in service, the work is engaged and gripped by the outer faces of the gripping blocks 7. Each gripping block has an inclined inner face adapted to engage a correspondingly inclined face on the tapered head 8' formed at one end of an expanding rod 8. The expanding rod 8 may be pulled longitudinally in one direction to force the gripping blocks 7 outwardly as shown in Figs. III and IV, thereby forcing said blocks into engagement with the work (not shown) and said rod 8 may be shifted in the opposite direction for the purpose of releasing the work from the mandrel. When the expanding rod is firmly held in the position shown in Fig. III, it retains the mandrel in its expanded condition, at the same time forcing the tapered portion 6 of the sleeve B into firm engagement with the hollow shaft 2. Spring rings 9, encircling the gripping blocks 7, tend to force the latter toward the axis of the sleeve B. These spring rings are preferably located near the ends of the gripping blocks 7, and the latter are preferably grooved to receive said rings.

The means for reciprocating the rod 8 to expand and contract the mandrel, preferably comprises an abutment device E consisting of an abutment block 10 screwed onto said rod 8 at a point beyond the hollow shaft 2, and a jamb nut 11 impinging against said block 10. The operating means also includes thrust members which engage opposite sides of the abutment device to shift the expanding rod 8 in opposite directions. This abutment device, consisting of the elements 10 and 11, is screwed onto the rod 8 so that it can be accurately adjusted to coöperate with different mandrels.

A tubular member 2' is screwed into one end of the hollow shaft 2 (Fig. III) so as to form a continuation thereof, and the expanding rod 8 extends from the outer end of said tubular member. Thrust dogs 12 are pivoted to the tubular member 2', and these dogs may be turned on their pivots for the purpose of engaging the abutment block 10 to shift the rod 8 in one direction. 13 designates a shiftable sleeve, slidably mounted on the tubular member 2', and provided

with converging inclined faces 14 which serve as cams for actuating the thrust dogs 12. Arms 15, extending from the shiftable sleeve 13, are fixed to a thrust collar 16 sleeve 13, are fixed to a thrust collar 16 5 adapted to engage the abutment nut 11. It is important to note that the shiftable sleeve 13 is rigidly connected to the abutment collar 16 by means of the arms 15. When the sleeve 13 is shifted from the position shown in Fig. II to the position shown by full lines in Fig. III, the inclined faces 14 engage the thrust dogs 12, thereby turning said dogs on their pivots, forcing them 10 into engagement with the abutment block 15 so as to move the abutment device and the rod 8 in one direction. The rod 8 is thus firmly pulled to the position shown in Fig. III, with the result of forcing the gripping blocks 7 away from the axis of the mandrel 20 and into engagement with the work (not shown). When the shiftable sleeve 13 is restored from the position shown by full lines in Fig. III to the position shown in Fig. II, the inclined faces 14 pass from the thrust 25 dogs 12, and the thrust collar 16 then engages the abutment nut 11 on the rod 8 to restore said rod to the position shown in Fig. II. The spring rings 9, encircling the gripping blocks 7, then force said blocks toward the axis of the mandrel to release the 30 work therefrom.

A shifter 17, pivoted at 18, is fitted to the shiftable sleeve 13 for the purpose of reciprocating the latter on the tubular member E. 35 19 designates a connecting rod, or link, connecting the shifter 17 to an operating lever 20, the latter being pivotally supported at 21.

It will now be understood that the mandrel can be easily and quickly expanded and contracted by merely oscillating the operating lever 20, and this can be done without stopping the machine.

A gear wheel 22, fixed to the hollow shaft 40 2, may be used for the purpose of transmitting power to other parts of the lathe, which are not shown for the reason that they do not form part of the present invention.

Figs. V and VI illustrate a modification 45 50 consisting of a work-receiving sleeve B', slotted at 23 to form yieldable gripping members 7'. This sleeve is also provided with a tapered portion 6' corresponding to the tapered portion 6 of the sleeve shown in 55 Fig. III. The inner faces of the yielding gripping members 7' are inclined to receive a tapered head 8^a at one end of an expanding rod 8^b, and this rod may be actuated by the operating means disclosed in Figs. I, 60 II and III.

I claim:

1. In a device of the character described, a 65 rotatable sleeve provided with yieldable gripping members adapted to engage the work, an expander for forcing said yield-

able members away from the axis of said sleeve and into engagement with the work, and means for shifting said expander in opposite directions parallel with its axis, so as to move the yieldable members toward and 70 away from the work, said means comprising an abutment device secured to said expander, thrust members surrounding said expander at opposite sides of said abutment device, said thrust members being 75 adapted to engage said abutment device to shift said expander in opposite directions, and means for actuating said thrust members.

2. In a device of the character described, a 80 rotatable sleeve provided with yieldable gripping members adapted to engage the work, an expander for forcing said yieldable members away from the axis of said sleeve and into engagement with the work, 85 and means for shifting said expander in opposite directions parallel with its axis, so as to move the yieldable members toward and away from the work, said means comprising an abutment device secured to said expander, 90 a pair of pivotally supported dogs adapted to engage one side of said abutment device to shift the expander in one direction, a thrust member adapted to engage the opposite side of said abutment device to shift the 95 expander in the opposite direction, and a shifter provided with means for actuating said dogs, said thrust member being secured to said shifter.

3. In a device of the character described, 100 a hollow rotatable shaft, a work-receiving sleeve secured to said shaft, said work-receiving sleeve being provided with yieldable gripping members adapted to engage the work, an expander comprising a rod having 105 an expanding member for forcing said yieldable members away from the axis of said sleeve and into engagement with the work.

said rod being extended from one end of said hollow rotatable shaft, and means for 110 shifting said expander in opposite directions parallel with its axis, so as to move the yieldable gripping members toward and away from the work, said means comprising an abutment device secured to the extended 115 portion of said rod at a point beyond said hollow rotatable shaft, thrust dogs pivoted to said hollow rotatable shaft and adapted to engage one side of said abutment device to move the expander in one direction, a 120 thrust member arranged at the opposite side of said abutment device and adapted to cooperate therewith to shift said expander in the opposite direction, a shiftable sleeve 125 slidably mounted on said hollow rotatable shaft, said shiftable sleeve being secured to said thrust member and provided with inclined faces which engage said thrust dogs to turn the latter on their pivots, and means 130 for reciprocating said shiftable sleeve.

4. In a device of the character described, a rotatable sleeve provided with yieldable gripping members adapted to engage the work, an expander for forcing said yieldable members away from the axis of said sleeve and into engagement with the work, and means for shifting said expander in opposite directions parallel with its axis, so as to move the yieldable members toward and away

from the work, said means comprising an 10 abutment device adjustably secured to said expander, thrust members adapted to engage said abutment device to shift said expander in opposite directions, and means for actuating said thrust members.

In testimony that I claim the foregoing I hereunto affix my signature.

GEORGE W. OSBORN.
